(57) **CLAIM**

The ornamental design for a chandelier center column, as shown and described.

DESCRIPTION

FIG. 1 is a perspective view of the chandelier center column of the present invention;

FIG. 2 is a left side view of the chandelier center column on an enlarged scale with the right view being a mirror image of FIG. 2 in accordance with the present invention;

FIG. 3 is a top view of the chandelier center column on an enlarged scale in accordance with the present invention; and, FIG. 4 is a bottom view of the chandelier center column on an enlarged scale in accordance with the present invention. Any dashed lines depict environment and are not part of the claimed design. In addition, the stippling shown in the drawing is for shading purposes, and does not form a part of the claimed design.
